Lorenzo Fairbanks of Philadelphia, Penn.

Letter Patent No. 2201 Dated Oct. 17-1865.

Design for a School Desk.

The schedule referred to in these letters Patent and making part of the same.

To all whom it may concern:

Be it known that I, Lorenzo Fairbanks, of Philadelphia, in the County of Philadelphia, and State of Pennsylvania, have invented or produced a new and original design for a Commercial School Desk, and I do hereby declare that the following is a full and exact description of the same, reference being had to the accompanying drawing and to the letter of reference marked thereon.

In order to enable others to make and use my invention or production I will proceed to describe it.

Our reference to the accompanying drawing which forms a part of this specification.

Fig. 1 is a front elevation.

Fig. 2, is a back elevation, and

Fig. 3, is a side view.

Similar letters refer to similar parts in the several views.

The front A and the sides B of my commercial school desk are constructed of solid panels, there is a railing C, around the top of it and extending along the sides to where the incline or working top C, of the desk commences, there is an opening or break d, in the front railing at or near the centre of it which projects above it and is so devised that a sign e, denoting the particular branch of business for which it is used can be attached over-head to it, the back of the desk is constructed as usual with drawers and recess for the legs and feet.

DFS. 2201

2

What I claim as my invention or production and desire to secure by Letters Patent is

The design for a commercial school desk as herein shown and described.

In testimony whereof I hereunto sign my name to this specification in presence of two subscribing witnesses.
